**LOCK CYLINDER SIDE BAR ACTUATED
 SWITCH**

Wilford B. Shrode, Huntington Woods, and Theodore H. Johnstone, New Baltimore, Mich., assignors to General Motors Corporation, a corporation of Delaware
 Filed May 7, 1963, Ser. No. 278,569
 13 Claims. (Cl. 200—44)

This invention relates to electrical switches and more particularly to the type of electrical switch that is actuated by side bar movement in an ignition lock cylinder. 10

It is an object of this invention to provide an electrical switch that is operable only upon insertion of the combination setting key into the lock cylinder without any further movement of that lock cylinder. 15

It is a further object of this invention to provide an electrical switch that is inexpensive to manufacture and which, also, can be mounted on a lock cylinder of an existing design. 20

Further objects and advantages of the present invention will be apparent from the following description, reference being had to the accompanying drawings wherein a preferred form of the invention is clearly shown. 25

In the drawings:

FIGURE 1 is a side elevation, with parts broken away, of a side bar actuated switch made in accordance with this invention; 30

FIGURE 2 is a sectional view on an enlarged scale taken along line 2—2 of FIGURE 1; 35

FIGURE 3 is a sectional view along line 3—3 of FIGURE 2;

FIGURE 4 is a partial sectional view taken along line 4—4 of FIGURE 3 showing the lock side bar in the retracted position; and 40

FIGURE 5 is a partial sectional view taken along line 4—4 of FIGURE 3 showing the lock side bar in the extended position. 45

FIGURE 1 illustrates a conventional ignition lock assembly 20 disposed in operating position within the lock cylinder side bar actuated switch, generally designated by numeral 50. In the embodiment of the invention as shown in FIGURE 1, a mounting escutcheon 38 cooperates with the threaded portion 44 of the switch to hold the switch body 51 in firm engagement with the metal support plate 76, such as an instrument panel of an automobile. 50

FIGURE 2 shows the lock cylinder and side bar actuated switch in cross section along the line 2—2 of FIGURE 1, the section being shown in enlarged scale. Section line 2—2 of FIGURE 1 is broken so as to show the operative parts of the mechanism in a single plane. The lock assembly includes a cylinder 24 having a slot 46E which slidably supports a tumbler 30E. The tumbler 30E is biased toward the top of the slot by the spring means 28. The tumbler spring 28 is held in firm attachment to the lock cylinder 24 by the tumbler spring retainer 26 which is secured to the lock cylinder 24. In perpendicular juxtaposition to slot 46 is a slot 48 which slidably supports the lock side bar assembly generally designated by numeral 22. The side bar springs 32 hold the lock side bar assembly 22 in biased contact with the tumblers 30A, 30B, 30C, 30D, 30E and 30F. The side bar springs 32 are interposed between the side bar 42 and the fixed side bar spring retainers 34. 60

The side bar assembly 22 as shown in FIGURE 2 by the solid line and in FIGURE 4 is in the fully retracted position while the dotted line 22 in FIGURE 2 and FIGURE 5 designates the lock side bar in the fully extended position. Referring now to FIGURE 4, each tumbler 30A, 30B, 30C, 30D, 30E and 30F has a groove similar

2

to the groove 40 but placed in a position on the side of the tumbler that will cause it to align itself with an adjacent slot as the key is inserted. This series of aligned slots, not shown, forms one elongated slot into which the side bar 42 moves as a key is inserted and thus disengages the side bar 42 from the radial locking slot 23 as best seen in FIGURE 3. In its fully extended position, the lock side bar 22 holds the arcuate leaf spring conductor member 58 away from the contact fastening screw 70 as the side bar extends past the body of the lock cylinder 24 through the radial locking slot. The arcuate leaf spring conductor member 58 is held in firm attachment with the arcuate-shaped conductor member 52 through the rivet fastener 56. The arcuate-shaped conductor member 52 is circumferentially mounted on the lock cylinder 24 and serves as a radial locator for the circular non-conductor member 54. 70

An insulating sleeve 68 is firmly embedded in the arcuate-shaped conductor member 52. The insulating sleeve 68 cooperates with the contact fastening screw 70 to hold the contact 64 in its operative position. Embedded in the circular non-conductor member 54 is the arcuate conducting means 62 which serves as a current path between contact 64 and the contacts 66. The contacts 66 are held in their operative position by being mounted in the wall of the contact retainers 72. The contact retainers 72 form a portion of the periphery of the housing or switch body 51. The circular non-conductor member 54 is rotatable within this housing by means of pressure exerted on the outwardly projecting member 60 which operates within the elongated peripheral slot 74. 80

In operation, as the key 36 is inserted into the lock cylinder 24, the tumblers 30A, 30B, 30C, 30D, 30E and 30F are forced down against their biasing springs 28 into the slots 46A, 46B, 46C, 46D, 46E and 46F. As the key 36 is pushed further into the lock cylinder up to the limit of its travel, each succeeding tumbler is pressed downward which causes the tumbler grooves 40 to align themselves. As this alignment is caused to take place, the biased lock side bar 42 moves into the now aligned tumbler grooves 40. This movement of the lock side bar serves a twofold purpose. First, it releases a radial lock which allows rotary movement of the lock cylinder 24 and also allows the arcuate leaf spring conductor member 58, by its own resilience, to come into contact with the contact fastening screw 70. At this point in the operation, the arcuate leaf spring conductor member 58 is disposed as shown in FIGURE 2 by the solid lines and the lock side bar 42 as disposed by the solid lines. The arcuate conductor means 62 being slidably rotatable between the contacts 64 and 66 and in contact therewith is capable now of transferring current from contact 64 to the contacts 66 and on to electrical equipment attached thereto. 90

The arcuate conducting means 62 is of sufficient radial length to allow the selection of one or more of the circuits that can be created between contacts 64 and 66 through movement of the outwardly projecting member 60. Similarly, upon retraction of the key from the lock cylinder, all of the circuits so energized are deenergized automatically, irrespective of the position of the outwardly projecting member 60. This deenergization is brought about because the switch is designed so that the series of tumbler springs 28 cumulatively provide greater force than the side bar springs 32 and, when the key is retracted from the lock cylinder, the tumblers are caused to move upwardly in slots 46A, 46B, 46C, 46D, 46E and 46F and force the lock side bar 42 towards the locked side bar spring retainer 34. This can only be done when the lock cylinder has been returned to the OFF position which causes the lock side bar to align itself with the radial locking slot 23. This lock side bar movement 100

also causes the arcuate leaf spring conductor member 58 to move away from the contact screw 70, thus breaking the circuit through the arcuate conducting means 62.

While the embodiment of the present invention, as herein disclosed, constitutes a preferred form, it is to be understood that other forms might be adopted, all coming within the scope of the claims which follow.

What is claimed is as follows:

1. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a first switching means engaging the lock side bar, and a second switching means having a plurality of contacts, said first switching means being responsive to movement of the lock side bar and thereby operated by the insertion of a key into the lock cylinder, said second switching means conductively engaging said first switching means thereby providing a control over the plurality of contacts by insertion of a key into the lock cylinder.

2. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a circuit breaking means associated with the lock cylinder, movable conducting means carried by the lock cylinder and responsive to movement of the lock side bar, a plurality of contacts engageable with said movable conducting means, said circuit breaking means and said movable conducting means being conductively engaged to conduct electrical current to one or several of said contacts, said circuit breaker means being operated by a movement of the lock side bar caused by the insertion of a key into the lock cylinder.

3. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a first switching means and a second switching means carried by the lock cylinder, said first switching means being carried by the lock cylinder and actuatable by the insertion of a key into the lock, said second switching means comprising a plurality of fixed contacts, an arcuate conducting means engageable with several of said fixed contacts, a circular non-conducting member carrying said arcuate conducting means, said first switching means having a movable contact engageable with said second switching means as a key is inserted into the lock.

4. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a first switching means carried by the lock cylinder and a second switching means carried by the lock, the first switching means comprising an arcuate shaped conductor member rotatably carried on the lock cylinder, an arcuate leaf spring conductor member, and a contact, said first switching means actuated by insertion of a key into the lock thereby allowing the lock side bar to assume an operative position, said second switching means comprising a plurality of contacts circumferentially carried with respect to the lock cylinder, an arcuate conducting member moving in response to the lock side bar, and a circular non-conducting member, said arcuate conducting member being imbedded in said circular non-conducting member, said first switching means providing a contact, when energized, for said second switching means.

5. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a first switching means comprising an arcuate shaped conductor member rotatably carried on the lock cylinder, an arcuate leaf spring conductor member biasedly engaging the lock side bar, and a contact, the lock side bar being disposed to hold said arcuate leaf spring conductor member away from said contact or upon insertion of a key into the lock to allow the arcuate leaf spring conductor member to move against the contact and energize said first switching means, said second switching means comprising a plurality of contacts, and an arcuate conducting means arranged to selectively slidably contact said plurality of contacts while engaging said circular non-conducting member and said first switching means, said arcuate conducting means carried by said circular non-conducting member.

6. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a switch body enveloping said lock, an arcuate shaped conductor member rotatably carried with respect to the lock cylinder and said switch body, an arcuate leaf spring conductor member carried by said switch body, and a contact, lock side bar being disposed to hold said arcuate leaf spring conductor member away from said contact or upon insertion of a key into the lock to allow the arcuate leaf spring conductor member to move against the contact and energize said first switching means, a second switching means comprising: a plurality of fixed contacts carried by said switch body, a circular non-conducting member, and an arcuate conducting means, said arcuate conducting means imbedded in said circular non-conducting member and arranged to constantly engage said arcuate leaf spring conductor member after the lock side bar frees said arcuate leaf spring conductor member, said circular non-conducting member having an elongated outward projection, said outward projection being a means for manual rotation thereof thereby allowing said arcuate conductor member to energize said plurality of contacts severally or jointly.

7. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a plurality of electric switches, at least one having a deflectable movable contact responsive to side bar movement and a fixed contact, said movable contact following the movement of the side bar to selectively engage and disengage said fixed and movable contacts.

8. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a plurality of electric switches, at least one, comprising: a fixed contact and a movable contact, said movable contact being biased to normally engage said fixed contact and being urged by the side bar to a position where it is disengaged from said fixed contact when the key is removed from the lock cylinder and the side bar is projected.

9. In a switch housing having a rotatable lock cylinder disposed therein, said lock cylinder including tumblers movable in response to a key to form a lateral slot, and a lock side bar movable from locking engagement with the

housing into said lateral slot to free the lock cylinder for rotation, an electric switch comprising: switch means including a fixed contact and a plurality of movable contacts, the lock side bar controlling the movement of a first movable contact of said switch means, a plurality of fixed terminals, and a manually shiftable contact for electrically connecting said fixed terminals selectively with the fixed contact of said switch means.

10. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a switch body mounted around the lock cylinder, a circuit breaking means carried by said switch body, movable conducting means, and a plurality of contacts carried by said switch body, said circuit breaking means comprising an arcuate shaped insulator member responsive to movement of a lever, an arcuate leaf spring conductor member responsive to movement of the lock cylinder, and a contact, said circuit breaking means and said movable conducting means being conductively engaged to conduct electrical current to one or several of said contacts carried by said switch body, said switch body being circumferentially mounted on the lock cylinder and being actuatable by the insertion of a key into the lock cylinder.

11. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a switch body, a circuit breaking means slidably carried on the periphery of the lock cylinder, movable conducting means, and a plurality of fixed contacts carried by said switch body, said circuit breaking means comprising: an arcuate shaped insulator member, an arcuate leaf spring conductor member carried by said insulator member and responsive to movement of the lock side bar, and a contact, said circuit breaking means and said movable conducting means being conductively engaged to conduct electrical current to one or several of said fixed contacts, said arcuate leaf spring conductor being in flexed contact with the lock side bar, said switch being opened or closed in response to the insertion or extraction of a key in the lock cylinder.

12. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a switch body, a circuit breaking means carried by said switch body, movable conducting means slidably carried with respect to said circuit breaking means, and a plurality of fixed contacts, said switch body having an elongated slot around its periphery, said circuit breaking means including an arcuate shaped insulator member, a deflectable arcuate leaf spring conductor member carried by said insulator member, and a fixed contact, said movable conducting means comprising, a circular non-conducting member rotatably

carried by said insulator member, an arcuate conducting means imbedded in said circular non-conducting member, and an outwardly projecting portion arranged for manipulation, said outwardly projecting member being a projection on the periphery of said circular non-conducting member, said movable conducting means having an inside and outside portion being disposed in slidable concentric relationship around said circuit breaking means, said arcuate conducting means being disposed to make contact with one or several of said plurality of contacts with its outside portion while its inside portion is in constant contact with said contact of said circuit breaking means, said disposition providing a selectively energizable circuit path to one or several of said plurality of contacts mounted in said housing.

13. In a switch housing having a rotatable lock cylinder disposed therein, said lock cylinder including tumblers movable in response to a key to form a lateral slot, and a lock side bar movable from locking engagement with the housing into said lateral slot to free the lock cylinder for rotation, an electric switch comprising: a housing, a circuit breaking means responsive to movement of the lock side bar, movable conducting means arranged circumferentially with respect to said circuit breaking means, and a plurality of contacts carried by said housing, said housing having an elongated slot around its periphery, said circuit breaking means comprising an arcuate shaped insulator member, an arcuate leaf spring conductor member deflectably carried by said insulator member, and a contact, said movable conducting means comprising, a circular non-conducting member, an arcuate conducting means imbedded in said non-conducting member, and an outwardly projecting member cooperating with the slot in the housing, said arcuate conducting means imbedded in one quadrant of said circular non-conducting member, said movable conducting means having an inside and outside portion being disposed in slidable concentric relationship around said circuit breaking means, said arcuate conducting means being arranged to make contact with one or several of said plurality of contacts with its outside portion while its inside portion is in constant contact with said contact of said circuit breaking means, said disposition providing a circuit path to one or several of said plurality of contacts, said projection providing an external means for control of said movable conducting means, said switch being initially energizable by a deflecting leaf spring conductor member in response to a movement of the lock side bar as a key is inserted into the lock cylinder.
